UNITED STATES PATENT OFFICE.

JOHN F. O'CONNOR, OF CHICAGO, ILLINOIS, ASSIGNOR TO WILLIAM H. MINER, OF CHAZY, NEW YORK.

DRAFT-RIGGING FOR RAILWAY-CARS.

1,265,490.

Specification of Letters Patent. Patented May 7, 1913.

Application filed August 12, 1916. Serial No. 114,520.

To all whom it may concern:

Be it known that I, JOHN F. O'CONNOR, a citizen of the United States, residing at Chicago, in the county of Cook and State of Illinois, have invented a certain new and useful Improvement in Draft-Rigging for Railway-Cars, of which the following is a full, clear, concise, and exact description, reference being had to the accompanying drawings, forming a part of this specification.

My invention relates to improvements in draft rigging for railway cars.

The object of my invention is to provide a durable friction draft gear.

In the drawings forming a part of this specification, Figure 1 is a side elevation partly in vertical longitudinal section of a draft rigging embodying my invention. Fig. 2 is a top plan view, partly in horizontal section on line 2—2 of Fig. 1. Fig. 3 is a cross section on line 3—3 of Fig. 1.

Referring to the drawings, the numeral 8 indicates draft members, or parts of the car underframe, to which the draft rigging is applied. Between the draft members a draft gear 10 is mounted, the same being supported by the tie plate 11, secured to the draft members and having associated therewith the usual rear stops 12—12, the front stops 13—13, the draw-bar 14, a draft yoke 15, which is secured to the draw-bar by means of the transverse key 16. A front follower is shown at 17. The draft gear 10 comprises a hollow shell 18, closed at its back by the preferably integral plate 19, and having mounted therein the spring elements 20 and the friction elements 21. The friction elements comprise the wedge 22 and a plurality of friction shoes 23. The said shoes in the preferred form of my invention, shown in Figs. 1 to 3 of the drawings, are four in number. Each of the shoes has an outer friction face 24 and an inner wedging face 25. The wedging face is formed between the shoulder 26 at its inner end and the shoulder 27 at its outer end, the said face being provided in an insert 28, which may be of a hardened metal, as for instance hardened steel, while the friction shoe may be made of cheaper material, as for instance malleable iron. The wedge is provided with a number of wedging faces, equaling the number of friction shoes, each of said wedging faces, as indicated at 29, being opposed

to one of the wedging faces of the shoes and bearing an anti-friction roller 30 mounted between the said wedging face of the wedge and the wedging face of the adjacent shoe. The wedge 22 is formed of two sections, the 60 throat 31 thereof bearing the wedging faces, preferably being of a hard material, as for instance hardened steel, and the head 32 may be of a softer and cheaper metal. The said head is provided at its inner end, as at 33, 65 with a depressed portion, or socket, to receive the inner portion or throat of the wedge therein. Each of the shoes is provided back of its wedging face with a recess, as at 34, forming a core opening which permits the satisfactory construction of the shoe without the employment of an excessive amount of metal.

The head 32 of the wedge is provided with a recess 36 to receive the nut 37 of the connecting rod 38, which passes through the wedge and is provided at its rear end with a head 39 which is received within the recess 40 in the rear plate 19 of the shell 18. A washer 41 is seated against the rearwardly 75 faced shoulders 42 provided upon the shoes, and against this washer the front end of the inner spring 43 is seated, the same being seated at its rear end against the internal boss 44, with which the rear end of the shell 80 is provided. An intermediate spring 45 is coiled about the inner spring, the said spring being seated at its forward end against the washer 41, and at its rear end against the rear end of the shell, an outer spring 48 in- 85 closing the other spring is seated at its forward end against the friction shoes and at its rear end against the friction shells. The said three springs constitute the spring elements 20 hereinbefore mentioned. The forward, or friction portion, of the shell 18 is provided with an annular groove 49 formed between the front shoulder 50 and the rear shoulder 51 with which the shell is 90 inferiorly provided. The said annular groove 100 is provided at intervals with longitudinally extended ribs 52, there being two of said ribs for each of the friction shoes, or eight in the preferred form of my invention illustrated in Figs. 1 to 3 inclusive. Against 105 each of said ribs is mounted a friction plate 53, the said plates being held at their ends between the shoulders 50 and 51. The said friction plates may be of a hard material, such as hardened steel, and are readily re- 110

movable when the friction elements are removed from the shell.

Each of the friction shoes 23 has its friction face 24 arranged in two planes, angular to each other, as indicated at the numerals 54, 54 in Fig. 3 of the drawings, the said face being so arranged that one portion engages one friction plate 53 and the other portion engages an adjacent friction plate 53. The 10 mounting of the said plates upon the ribs 52 serves to support the said plates along their longitudinal center and also permits a perfect engagement between the friction shoes and the said plates.

15 From the foregoing description, the action of the draft gear will be readily understood. On inward movement of the draw-bar, as in buffing action, the friction elements are forced inwardly in reference to the shell, the 20 wedge spreading the friction shoes and forcing them into frictional engagement with the friction plates, the said inward movement of the friction elements being resisted by the spring elements. On forward movement of 25 the draw-bar, the yoke draws the shell forwardly and the same action of the parts within the shell occurs as in buffing action.

Upon wear of the friction plates, the same 30 can be readily replaced and by reason of the inserts in the friction shoes for the anti-fric-

tion rollers to bear against a shoe of comparatively soft material may be used, having a wedging face of hard material, and also the said wedging face may, if desired, be readily renewed.

35

I claim:—

1. In a draft rigging for railroad cars, a draft gear comprising a shell, friction elements including friction shoes within the shell, a plurality of removable friction plates 40 within the shell, adapted to be engaged by the friction shoes, the shell being provided with longitudinal ribs, the friction plates being mounted on said ribs.

2. In a draft gear, a shell, friction elements including friction shoes within the shell, friction plates mounted within the shell, the shell being provided with internal shoulders and having longitudinal ribs between said shoulders, the said friction 50 plates being mounted between said shoulders and upon said ribs.

In witness that I claim the foregoing I have hereunto subscribed my name this 7th day of August 1916.

JOHN F. O'CONNOR.
